ELASTIC TAPE ATTACHING MECHANISM

Joseph Galkin, New York, N. Y.

Application September 14, 1936, Serial No. 100,778

6 Claims. (Cl. 112—2)

This invention relates to sewing machines designed for attaching an elastic tape to woven fabrics, and particularly to the waistbands of bloomers for the purpose of providing frictional engagement of the garment on the waists of persons having different size waistlines.

The elastic tape is in superposed relation with the waistline edge of the woven fabric and is attached to the fabric while under tension, so that when the stitching operation is finished the tensioned and stretched elastic tape returns to its originally shorter length and gathers the waistband portion of the woven fabric.

It is a well known fact that when feeding two superimposed fabrics through the usual sewing machine having a lower feed only, the lower ply being engaged by the 4-motion feed dog tends to feed faster than the superimposed ply which engages the non-advancing presser foot. The upper ply not being directly engaged by the lower feed dog has a tendency to drag. This tendency to unequal feeding is aggravated when one of the fabrics to be fed is an elastic tape under tension.

An object of this invention is to provide a pull-feed mechanism or auxiliary feed located in the rear of the main feed and in closely spaced relation from the stitch forming mechanism, and devices cooperating therewith whereby an elastic tape may be passed from the front of the machine below the auxiliary feed so as to be engaged and pulled while fed to the stitching mechanism in a tensioned condition.

Another object of this invention is to provide a sewing machine having a duplex feeding mechanism comprising an auxiliary toothed pull-feed roller mounted for vertical motion close to the rear of the presser-foot, with means for moving the auxiliary pull-feed roller so that it may be given a feed stroke of the same length as the main feed.

Another object of this invention is to mount the tape-guide in pivotal relation with the front of the presser-foot so as to permit said guide to be swung upwardly and away from the needles to facilitate the threading of the needles.

Another object of this invention is to groove the pull-feed roller and to insert wires in the grooves, the ends of the wires being secured in the roller housing and serving to throw off the fabric from the roller and prevent the fabric from being carried into the roller housing and jamming the feed mechanism.

Another object of this invention is to make the tape-guide with two spring-pressed jaws which automatically open and close depending on the

thickness of the elastic and to provide a dial for controlling the pressure between the jaws. The dial gives a visual set indication of the overall length of the finished waistline of the bloomer and makes it possible to exactly pre-determine the size of the finished bloomers.

With the above and other objects in view, the invention will be hereinafter more particularly described and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front view of a sewing machine embodying my tape guiding mechanism whereby an elastite tape may be attached to waistbands of bloomers.

Figure 2 is a rear view of the sewing machine embodying my invention.

Figure 3 is an end view of the sewing machine.

Figure 4 is a side view of the tape guide mechanism, partly in section.

Figure 5 is a top view of the supporting means for the tape guide mechanism and showing a tape threading aperture.

Figure 6 is a plan view of the presser foot.

Figure 7 is an elevation of the assembled sewing machine, tape guide, and a vertically mounted tape supply spool and shows two positions which my tape guide may assume.

Figure 8 is a cross-sectional view of the feed roller and the roller housing, showing means for preventing jamming of the feed roller mechanism.

Figure 9 shows a modified mounting for the feed roller whereby the roller is supported from below by the work supporting base.

Figure 10 is an end view of the tape guide.

In the illustrated embodiment of the invention, the numeral 10 indicates the work supporting base of a sewing machine embodying my invention and which comprises the usual standard 11, 45 having an overhanging arm 12 with a head 13 at its free end. In the head 13 is journalled the usual reciprocatory needle-bar 14 carrying two spaced needles 15. The needle-bar is reciprocated by a lever 16 mounted on a pivot shaft 17. 50 A looper 18 is oscillated and cooperates with the two spaced needles. The looper thread interlocks with the needle threads to form stitching as is well known in the sewing machine art. The material worked upon is held down by a presser 55

foot 19 resting on a needle plate 20 secured to the work supporting base 10.

Projected through the needle-plate 20 is a work-advancing feed-dog 21 having actuating mechanism (not shown) which may be of any usual lower four-motion type of feeding mechanism. Opposed to the feed-dog 21 is the presser-foot 19 having its shank 22 suitably secured to the lower end of a presser-bar 25 vertically movable in the head 13 in the usual manner. Pressure is maintained upon the presser-foot 19 by a leaf spring 23 pressing upon the presser-bar 25.

The pull-feed roller 26 is rotated by a shaft 27. The roller 26 is mounted in a housing 28. The housing 28 is fastened to a vertical lifter pin 29 having a head 34 and which is slidably mounted for vertical motion in bearings 31. The housing 28 is also mounted for vertical sliding motion on a guide pin 32 secured in the head 13. The presser-bar 25 may be raised by a lever 37. When the presser-bar 25 is raised by the lever 37, it also contacts the collar 34 and raises the lifter pin 29, the housing 28 and the pull-feed roller 26. A leaf spring 38 bears at one end on a spring rest 39 and at the other end on a ball 40 seated in the top face of the housing 28 and this pressure is transmitted to the roller 26.

An adjusting screw 42 threaded in a bracket 43 acts against the spring 38 and forces the roller 26 yieldingly in a downward direction against a concave and arcuate seat 44 extending upwardly above the work supporting base 10. The lowest level of the seat 44 is slightly above the upper level of the needle plate 20. As shown in Figure 7, it will be noted that the toothed roller 26 has three teeth 36 in pressure contact with the concave seat 44 which function to positively grip and feed the elastic tape at a plurality of points positioned in an arc of a circle.

The lifter pin 29 and the auxiliary guide pin 32 jointly maintain the roller 26 in vertical sliding relation and in alignment with the arcuate seat 44.

It is desired that a positive rotary step-by-step driving motion be imparted to the shaft 27, to a universal joint 50 and to the pull-feed roller 26 so that it may be given a feed stroke of the same length as the feed-dog 21. For this purpose I employ an oscillatable clutch detent carrier 55 mounted within an annular casing 56, fixed to the shaft 27, as best shown in Figure 1. A cover plate 51 having an integral arm 58 has been fastened to the clutching detent carrier 55. As is shown in Figure 2, the arm 58 is pivotally connected at one end to a vibrating connection 59 operated by an eccentric 60 on the main shaft 61.

In order to positively prevent reverse movement of the shaft 27, I have provided a braking detent carrier 65 mounted within the casing 56. A cover plate 66 having an arm 67 has been fastened to the braking detent carrier 65. The arm 67 is secured to the bracket 43 which is fastened to the base plate 47 of the sewing machine.

The clutch detent carrier 55 and the braking detent carrier 65 are mounted on the shaft 27 to work in opposite directions and may be in the form shown and described in Patent No. 1,985,406 issued to Nathan B. Galkin, dated December 25, 1934. The clutch arm 58 is secured to the cover plate 51 and to the clutch detent carrier 55. The swing of the arm 58 imparts an intermittent rotation to the casing 56 and through a screw 68 to the shaft 27. The braking detent carrier being fixed to the sewing machine frame,

causes the shaft 27 to be gripped at the end of each feeding movement without any lost motion or back-lash at the feed roller 26.

Screwed to the head 13 is a bracket 69 having an overhanging pivot 70 and a fixed collar in which are two diametrically positioned notches 71, positioned about 180 degrees apart. An arm 72 has been rotatably mounted on the pivot 70 and a lever 73 has been fulcrumed on a screw 74 and has a lug 75 designed to seat in one of the notches 71. A spring 76 secured between the arm 72 and the lever 73 serves to press the lever into engagement with one of the notches 71 so as to lock the arm 72 on the pivot 70 in an operative position shown in full lines or in an inoperative position shown in dot-and-dash lines in Figure 7.

Pivotedly mounted on a pivot 77 in the arm 72, shown in Figure 4, is a tape engaging element 78. Extending from the arm 72 through a suitable aperture in the element 78 is a tension post 79 carrying an adjusting nut 80 between which and the element 78 is disposed a leaf spring 81. By adjusting the nut 80 a predetermined pressure is exerted upon the arm 72 by the element 78.

A lever 82, best shown in Figure 10, has been fulcrumed on a screw 83 in an angular extension of the arm 72 and has a lug 84 extending under the thumb engaging portion 85 of the lever 73. The lower end 86 of the lever 82 is angularly bent, as shown in Figure 9, to engage the rear surface of the tape engaging element 78. It will thus be seen that when the lever 73 is actuated, the lever 82 forming a connection between the lever 73 and the tape engaging element 78, causes the said element to move away from the arm 72 and to release the tension on the tape. The lever 73 thus releases the tension on the tape at all times except when the tape guide 92 is in one of its two positions.

The arm 72 and the tension element 78 are directed parallel to and spaced from the line of seam formation but have angularly directed lower end portions 87 disposed crosswise of the line of seam formation and it is between these end portions that an elastic tape is directed in line of seam formation and under tension to the needles 15. As best shown in Figure 1, it will be seen that the means for releasing the pressure between the jaws is positioned to one side and clear of the tape engaging means.

On the pivot shaft 70 are slideable collars 88 and 89, best shown in Figure 5. The collars may be adjusted on the shaft 70 to provide between them a passageway for the tape to be stitched by the needles 15. A pin 90 fastened to the collar 88 and slideable in an aperture in the collar 89 is positioned in parallel spaced relation from the shaft 70 and forms a threading aperture 91 for the introduction of the tape into the tape guiding attachment 92.

The presser-foot 19 has at its front end a turned-up toe 93 provided with needle apertures (not shown). On the upturned toe portion 93 of the presser-foot 19 are slideable members 94 and 95, best shown in Figure 6. The members 94 and 95 may be slideably adjusted on the presser-foot 19 to provide between them a threading guide 96 in alignment with the threading aperture 91 to guide the tape from the delivery end of the tape guiding attachment 92 under the presser-foot 19 in properly spaced relation with the needles 15. As shown in Figures 1, 5 and 6, it is to be noted that the tape threading aperture 91 and the tape threading guide 96 are considerably

- wider than the distance between the needles and that the said aperture and guide are spaced in offset relation with the needles so that only one edge of the tape is directed between the needles.
- 5 Screwed upon the needle plate 20 is a hemmer 97 having a scroll providing a curved passageway to fold the margin of a body material in line of seam formation. Both needles 15 penetrate the elastic tape and the body fabric.
- 10 The outer face of the threaded member 80 has radial lines and numerals indicating equal divisions forming a dial. The dial 80 may be set by means of a pointer 98 to visually indicate the amount of tension between the arm 72 and the
- 15 tension element 78. It is thus possible, by setting the dial and controlling the tension, to pre-determine the length of the finished waist band and the size of the bloomers.
- As shown in Figure 7, there has been provided 20 a tape supply spool 100 mounted for rotation while supported endwise on a thrust bearing 101. The bearing is supported on a bracket 102 secured to a stand 103.
- A leaf spring 104 extends from the bracket 102 25 and has a ball-shaped elevation 105 struck-up therefrom and contacting with the lower side disk 106 of the tape supply spool 100. The pressure of the leaf spring 104 against the spool controls the rotation of the spool and prevents spinning. The spring controlled and thrust bearing supported spool slightly tensions the tape during its unwinding and prevents sudden unwinding of the tape 107.
- A bar 108 extends vertically from the sewing 30 machine and carries a tape eyelet 109 at its upper end for receiving the tape from the supply spool.
- The self adjustable tape guiding attachment 92 causes a uniform frictional grip on the portion of the elastic tape positioned close to the presser-foot 19 so that while the elastic tape is fed through the sewing machine, it is uniformly stretched between a point close to the front of the presser-foot and a point close to the rear of the presser-foot. The elastic tape is sewed on 35 to the waist band portion of the fabric in a stretched condition. The elastic tape on the finished waist band draws back to its normal length and causes the waist band to be gathered.
- To prepare for the stitching operation, the 40 lever 73 is depressed at the thumb engaging portion 85 and an elastic tape is drawn through the tape guiding attachment 92, and inserted under the presser-foot 19 with the roller 26 nipping the end of the tape against the arcuate seat 44.
- 45 The body material is then inserted into the hemmer 97 and under the tape. The feed dog 21 feeds the body fabric while the roller 26 feeds the elastic tape. The result of the combined action of the upper and lower feeding is that an equal length of fabric and tensioned elastic tape are simultaneously fed through the sewing machine. The pull-feed roller 26 assists in carrying away the stitched work and thereby prevents bunching of the work back of the presser-foot 19 under the 50 action of the tensioned tape.
- As shown in Figure 2, the roller 26 has two 55 peripheral grooves 30 to receive circularly bent wires 35, best shown in Figure 8. Both ends of the wires 35 are fastened in the roller housing 70 60 65 75 80 85 90 95 100 105 110 115 120 125 130 135 140 145 150 155 160 165 170 175 180 185 190 195 200 205 210 215 220 225 230 235 240 to move in a line through said sewing machine, said tape threading aperture and threading means being spaced in offset relation with the sewing machine needles so as to cause only one edge portion of the tape to be attached on top of said body material.

3. In a sewing machine for attaching tensioned elastic tape to a body fabric, a two-position tape guide comprising a pivot supported from the head 10 of said sewing machine, a tape threading member slidably mounted on said pivot, spring-pressed jaws rotatably mounted on said pivot in spaced relation from said threading member, said jaws having angular extensions, said tape threading member and said angular extensions being 15 jointly designed for guiding a tape in alinement with the line of stitching, and means for adjusting the pressure between said jaws, said jaws being adapted for movement from an operative position to an out-of-the-way position, said pivot having a member of irregular outline fixed thereon for raising one of said jaws and releasing the tension of said jaws on the tape during motion between said two positions, said jaw tension releasing means being positioned to one side 20 and clear of said tape engaging means.

4. In a sewing machine for attaching tensioned elastic tape to a body fabric, a two-positioned tape guide comprising a pivot supported from the 30 head of said sewing machine, spring-pressed jaws rotatably mounted on said pivot, said jaws having angular extensions, said angular extensions being designed for guiding a tape in alinement with the line of stitching, means for adjusting the 35 pressure between said jaw extensions and in-

dicating the amount of tension, said jaws being adapted for movement from an operative position to an out-of-the-way position, said pivot having a member of irregular outline fixed thereon for raising one of said jaws and releasing the 5 tension of said jaw extensions on the tape during motion between said two positions, said jaw tension releasing means being positioned to one side and clear of said tape engaging means.

5. In a sewing machine for attaching tensioned 10 elastic tape to a body fabric, a two positioned tape guide comprising a pivot supported from the head of said sewing machine, spring-pressed jaws rotatably mounted on said pivot, said jaws being designed for guiding a tape in alinement with 15 the line of stitching, means for adjusting the pressure between said jaws and indicating the amount of tension, said jaws being adapted for movement from an operative position to an out-of-the-way position, said pivot having a member 20 of irregular outline fixed thereon for raising one of said jaws and releasing the tension of said jaws on the tape during motion between said two positions, said jaw tension releasing means being positioned to one side and clear of said tape 25 engaging means.

6. The invention as defined in claim 2 wherein said roller has peripheral grooves and said roller mounting has circularly bent wires secured thereto, said wires being disposed in said grooves and forming a guard which causes the fabric passing underneath said roller to continue in a straight line along the line of feeding. 30

JOSEPH GALKIN. 35
